(57) **CLAIM**

The ornamental design for a storage container as shown and described.

DESCRIPTION

FIG. 1 is a perspective view of a storage container embodying the invention.

FIG. 2 is a first side view of the storage container of FIG. 1.

FIG. 3 is a second side view of the storage container of FIG. 1.

FIG. 4 is a third side view of the storage container of FIG. 1.

FIG. 5 is a fourth side view of the storage container of FIG. 1.

FIG. 6 is a top view of the storage container of FIG. 1; and,

FIG. 7 is a bottom view of the storage container of FIG. 1.

Portions of the storage container shown in broken lines form no part of the claimed design.

1 Claim, 7 Drawing Sheets
